EQUILATERAL TRIANGULAR BILLIARD
AND POOL TABLES

Hermenio Santiago, Bronx, N.Y.

Application November 5, 1958, Serial No. 771,980

2 Claims. (Cl. 273—4)

This invention relates generally to gaming tables and, more particularly, to tables on which games partaking of the nature of pool and billiards may be played.

Heretofore, the games of pool and billiards generally have been played with balls and a cue stick on rectangular-shaped tables. The pool tables have pockets at the corners and at the middle of the long sides into which the balls are hit. The billiard tables have no pockets, the object of the game being to hit two of three balls with another ball on each shot.

It is an object of the present invention to provide a convertible table on which both pool and billiards can be played as desired.

A specific object is to provide a table that is readily convertible for use either as a pool table or a billiard table.

Another object of the invention is to provide an equilateral triangular table for selectively playing either pool or billiards.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a table embodying my invention in use as a pool table.

Fig. 2 is a side elevation as viewed along the line 2—2 of Fig. 1.

Fig. 3 is an enlarged cross section taken along line 3—3 of Fig. 1.

Fig. 4 is a bottom plan view of the table.

Fig. 5 is a view similar to Fig. 1 showing the table converted for use in playing billiards.

Fig. 6 is an enlarged cross-sectional view taken on the plane of the line 6—6 of Fig. 5.

Fig. 7 is a perspective view of the pocket closure device.

Referring to the drawings in detail, a table 10 embodying the invention is shown as comprising a thick flat slab 12 of triangular shape, fixed horizontally on legs L. The slab is preferably formed of wood, slate, stone or any other suitable material and has a smooth, level rolling top surface, preferably covered with any suitable fabric 14, such as felt, smoothly drawn without wrinkles and secured in position in any suitable manner. The legs L are preferably formed of wood.

Rails 13, 15 and 16, preferably of wood, are fastened to the sides of the slab by adhesive or the like and extend above the top surface of the slab as indicated at 18, thereby fencing in the top surface thereof. The end meeting edges of the rails are secured to each other by adhesive or the like, forming mitre joints 20 between the rails.

At each corner of the slab 12, the portions 18 of the side rails extending above the top surface of the slab

2

have their end meeting edges cut away as indicated at 24. The corners of the slab 12 are similarly cut away as indicated at 26, the cut away portions facing each other and forming corner pockets 28. Midway the corners, 5 the extending portion 18 of each rail is similarly cut away as indicated at 30, and the adjacent side edge of the slab is cut away as indicated at 32, the cut away portions facing each other and forming side pockets 34. The cut away portions forming the corner and side pockets extend downwardly to a point remote from the bottoms of the slab and side rails.

Each of the side rails 13, 15, 16 is formed with a dovetail groove 36 along the inner surface thereof and lining each groove 36 is a sheet metal lining 38. Midway between each side pocket 34 and each end pocket 28, the material of the protruding portion 18 of each rail is bored, providing a hole 40 extending from the outer surface to the groove 36 in the inner surface of the rail. The hole is counterbored around its outer opening providing an elongated countersunk groove 42 on the outer surface of the rail.

A strip of rubber, triangular in cross section, constituting an elastic cushion 44, is slidably mounted in the lining 38 on each side rail, with its apical end 46 projecting outwardly of the groove and inwardly of the rail, over the top surface of the slab. The apical end 46 of the strip is covered with fabric material 48 similar to the material on the top surface of the slab. The rubber strip is gripped between the sides of a flanged base plate 50 of dovetail shape in cross section, slidably fitted in the groove. The cushion is secured in the groove 36 by means of a headed bolt 52, the threaded shank 54 of which extends through the hole 42 in the rail 16 and through a threaded hole 56 in the base plate 50. The head of the bolt is positioned in the countersunk groove 42. Each base plate 50 is provided with a pair of such holes 56, the holes being closely spaced from each other. The ends of the cushions 44 are beveled and terminate at the ends of the side and end pockets leaving a clearance in front of each pocket to allow the balls to roll into the pocket.

The slab 12 is formed with a main gutter or runway 60 adjacent the lower surface thereof, extending from the pocket 28 at the apical end to the side pocket 34 at the 45 diametrically opposite side thereof, in rail 13, the gutter slanting downwardly from the end pocket to the side pocket 34. Branch gutters 62 extend downwardly from the other corner pockets 28 to and communicate with the adjacent end of the main gutter 60. Similar branch 50 gutters 64 extend downwardly from the side pockets 34 inside rails 15 and 16 to and communicate with the main gutter. A recess is formed in the rail 13 at the intersection of the main gutter 60 and the side pocket 34, in 55 communication with the end of the gutter, and mounted in said recess below said intersection is a flanged pan 66 for receiving the balls that roll into the main gutter from the pockets.

In Fig. 1, the table 10 is shown arranged for use in 60 playing pool or pocket billiards, with playing balls 67 racked in position thereupon within a rack 69 preparatory to play. The invention, however, contemplates the conversion of the table for use in playing the game of billiards wherein the player impels the ball so that it will carom upon two other balls, wherein the cushions are continuous and wherein no pockets are needed, such as shown in Fig. 5. For this purpose, a plurality of cushion inserts or units indicated generally at 70 are provided. Each cushion insert or unit 70 includes a short length of 65 rubber 72, similar in shape to the strips constituting the cushions 44. The ends of the length of rubber 72 are beveled in directions opposed to the directions of beveling.

of the ends of the cushions 44 so that the apical end of the length of rubber 72 is longer than the base portion thereof. The length of rubber 72 is covered by a cover of fabric 74 similar to the fabric covers of the cushions 44. A flanged base plate 76 reinforces the base portion of the rubber 72 and a similar flanged plate 78 is sleeved over the plate 76. An inverted U-shaped clamp 80 is yieldingly connected to the flanged plate 78 in spaced relation thereto by means of a compression coil spring 82 interposed between the plate and clamp, with one end anchored to a lug 84 embedded in the plate 78 and with its other end secured to a pin 86 secured to clamp 80.

In order to convert the table 10 for use in playing billiards, the bolts 52 are loosened from the base plate 50 and the cushions 44 with the base plates are slid along the grooves 36 to the corners of the table where the adjacent beveled edges of the cushions will meet face to face to form mitre joints thereat and to cover the entrances of the corner pockets. The cushions 44 are each secured in moved adjusted position by threading the bolt 52 into the other threaded hole 56 in the base plate 50 which is now aligned with the bolt. The separation of the cushions widens the gaps between the opposite ends of the cushions adjacent the side pockets 34. In order to fill the resulting gap at each side pocket, a cushion insert or unit 70 is positioned between the adjacent ends of the cushions 44. This is accomplished by slipping the U-shaped clamp 80 downwardly over the top edge of the side rail so that the end edges of the length of rubber 72 fits between and engages the end edges of the adjacent cushions 44 thereby closing the gap thereat. The beveled end edges of the cushions 44 coacting with the beveled end edges of the insert or unit 70 hold the insert or unit 70 against outwardly acting forces. The inserts or units are held against inward acting forces by the springs 82 and the clamps 80.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. A convertible game table comprising a triangular-shaped slab, legs supporting said slab at the corners

thereof, a fabric covering over the top surface of said slab, said covered surface constituting a playing surface, rails secured to the sides of said slab and protruding above its top surface, said slab and rails having pockets at the corners thereof and midway said corners, said slab having a main gutter and branch gutters communicating with said pockets for receiving balls falling into said pockets, said slab having a recess in one side thereof below one end of the main gutter, a pan mounted in said recess, the open top of said pan communicating with the adjacent end of the main gutter for receiving balls from said main gutter, an elastic cushion slidably mounted on the inner surface of each rail between each pair of pockets therealong, the ends of the cushions adjacent the corner pockets adapted to cover the corner pockets when in moved position, the opposite ends of said cushions being spaced apart when in moved position, cushion inserts detachably mounted on the side rails and closing the spaces between said other opposite ends of the cushions when the cushions are in moved position, and means for positively retaining said cushion inserts in said spaces including base plates on the cushion inserts and inverted U-shaped clamps yieldingly carried by the base plates.

2. In a combined pool and billiard table, a removable cushion insert similar in cross section to the cushion of the table, said insert including a short length of solid rubber and a flanged base plate therefor, and means for positively retaining said insert in the pocket opening of the cushion of the table, said means comprising a lug embedded in the plate, and an inverted U-shaped clamp connected to said lug, said connection including a coil spring interposed between the lug and clamp with one end anchored in the lug and its other end secured to a pin in the clamp.
